(57) **CLAIM**

The ornamental design for a motor vehicle and/or toy replica thereof, as shown and described.

DESCRIPTION

FIG. 1 is a left, front perspective view of a motor vehicle and/or toy replica thereof showing our new design;

FIG. 2 is a left, rear perspective view thereof;

FIG. 3 is a left side elevation view thereof, the right side elevation view being a mirror image;

FIG. 4 is a top view thereof;

FIG. 5 is a front elevation view thereof; and,

FIG. 6 is a rear elevation view thereof.

The bold broken lines illustrate portions of the motor vehicle and/or toy replica thereof and form no part of the claimed design.

The claimed design is indicated by the relatively dark portions in the figures, while the relatively light portions within the bold broken lines are environmental and form no part of the claimed design.
